UNITED STATES PATENT OFFICE.

CHARLES D. ROGERS, OF PROVIDENCE, RHODE ISLAND, ASSIGNOR TO THE AMERICAN SCREW COMPANY, OF SAME PLACE.

DIE FOR ROLLING DRIVE-SCREWS.

SPECIFICATION forming part of Letters Patent No. 408,528, dated August 6, 1889.

Application filed February 12, 1889. Serial No. 299,669. (No model.)

To all whom it may concern:

Be it known that I, CHARLES D. ROGERS, a citizen of the United States, residing at Providence, in the county of Providence and State of Rhode Island, have invented certain new and useful Improvements in Dies for Rolling Wood-Screws; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The invention herein described relates to a die for producing a peculiar wood-screw, for which I have this day made an application for a patent. The die must produce on the surface of a screw-blank, first, shallow spiral grooves having transversely a curved surface; second, threads at the edges of the groove raised slightly above the normal surface of the blank, and, third, a spiral normal portion of the blank's surface between two adjacent threads. The die is straight, having its working-face provided with diagonal ribs, grooves, and plane surfaces corresponding to the grooves, threads, and normal surface of the blank. The ribs rise, in part, above the plane portions of the die, and extend slightly below those surfaces, forming along the sides of the ribs grooves which produce the thread of the screw. The ribs are convex transversely, and in operation are to be forced into the blank to the extent that they rise above the plane portions of the die-surface. The metal which is displaced should flow into and fill the grooves formed between the ribs and the plane portions of the die. The faces of the ribs which first come in contact with the blank should be a little lower than those which complete the grooves, in order that the displacement of the metal may be gradual.

In the annexed drawings, Figure 1 represents one form of my improved wood-screw, a portion of the screw being in section to show the form of the groove and threads, one continuous groove being employed. Figs. 2 and 3 are cross-sectional views taken on lines $x x$ and $w w$, respectively. Fig. 4 is a per-

spective view of my improved screw having a slightly-modified form. A portion of this screw is also broken away to show the form and arrangement of the grooves and threads, which have a steeper inclination or pitch than the threads shown in Fig. 1, the thread, as drawn in Fig. 4, being what is termed a "double" thread and having two continuous grooves. Fig. 5 is a cross-sectional view taken on line $o o$ of Fig. 4. Fig. 6 is a front view of the die, in reduced scale, showing the working-face, the die being more particularly adapted to produce the threads and groove shown in Fig. 1. Fig. 7 is an end view of the die. Fig. 8 is an enlarged transverse sectional view taken on line $x x$ of Fig. 6. Fig. 9 is a front view of the die, also in reduced scale, having the ribs and grooves arranged to produce the double grooves and threads shown in Fig. 4, and Fig. 10 is an end view of the die.

In Fig. 1 is illustrated the conditions required in the die itself, and, as shown in Fig. 6, the shallow spiral continuous groove a , having transversely a curved form, and the threads c at the edges of the groove raised slightly above the normal surface m of the blank, have, respectively, their counterpart in the diagonal raised ribs a' , grooves c' , and plane surface m' of the straight die D. In order to produce the threads and groove on the point portion p of the screw, Fig. 1, the face of the die is raised along its lower edge, as at t^2 , Fig. 7. The inclination of the ribs and grooves is such as to produce single-groove screws, the blank being entered at the right of the die, the ribs a' first acting upon the point of the blank and gradually form the groove a and threads c upon the surface of the blank. The dotted lines n^4 at the sectional portion of Figs. 1 and 4 indicate the relative pitch or inclination of the screw-threads. The transverse area of the portion of a rib a' , extending above the general face or surface m' of the die, is practically equal to the area of the two grooves c' , extending below said surface. Consequently the metal of the blank which is displaced by the ribs of the dies should flow into and just fill the grooves c' , thereby producing a screw having a spiral groove a and screw-threads c , raised

at the edges of the groove above the normal surface of the blank, and having a spiral normal surface m between the threads.

In producing the screw shown in Fig. 4, and 5 having a double groove, the angle of the ribs and grooves of the die form an inclination of about forty-five degrees, as shown in Fig. 9. The ribs a' are very short at the end of the die (right) where the rolling commences, and 10 gradually increase in length therefrom until the maximum is reached at the opposite end of the die. A pair of dies thus made and suitably mounted would seize a blank at a 15 point midway of the portion to be threaded and gradually form the grooves and threads therein from said point in either direction simultaneously, the thread produced not extending to the point.

As before stated, the face of the ribs at the 20 entering end, which first come in contact with the metal, should be a very little lower than the faces of the ribs farther along, which complete the grooves in the screw, in order that the displacement of the metal may be 25 gradual. In the use of the die the plane portions m' should be brought into contact with the normal surface m of the blank which is to be preserved in order to prevent its distortion by the displacement of the metal to 30 form the grooves.

It will be understood that two dies D like that described are to be used in making

screws, and that the blank is rolled between them as they move past each other in opposite directions. They are to be operated in a 35 machine similar to that described in a patent granted to me September 20, 1887, No. 370,353, and also in my patent of September 4, 1888, No. 389,168.

The amount of metal displaced by the action of the ribs a' to form the groove a and threads c is indicated by the dotted line at t , Fig. 3, being a transverse sectional view of the screw represented in Fig. 1, and Fig. 5 shows a corresponding displacement of the 45 metal of the screw shown in Fig. 4.

I claim—

A die for rolling screws, provided with diagonal ribs and grooves for impressing a spiral groove into the metal of a screw-blank and 40 raising the metal at the edges of the groove above the normal surface of the blank to form the threads of a screw, and with plane surfaces between the ribs corresponding to the 45 normal surface of the blank to preserve such surface from distortion by the action of the ribs in forming the groove and threads.

In testimony whereof I have affixed my signature in presence of two witnesses.

CHARLES D. ROGERS.
